UNITED STATES PATENT OFFICE

ELDRIDGE R. BOYLE, OF BOSTON, MASSACHUSETTS

CARRIER FOR GARMENTS

Application filed October 18, 1928. Serial No. 313,278.

This invention deals with carriers for holding garments in neatly folded arrangement without creasing them even though they are then packed in suit cases, trunks or the like for a considerable space of time. In carrying out this purpose it is also essential to allow proper spacing for the various folds, sleeves or the like that may be found on the garments. This has been accomplished by giving special form to the bars upon which the garments are wound so that the folded portions, such as sleeves or pleats will be given added space within the bounds of the device.

In arranging clothing on a carrier of this type it is desirable that means be provided for handling garments of various sizes and proportions, and to this end the form for the garment is made adjustable in its position relative to the carrier itself. The mode of adjustment disclosed in this description admits of ready operation and at the same time prevents undesirable twisting or pivoting of the form relative to its supporting hook. The latter takes a special shape and the associated parts used with it allow the collar of the garment to hang naturally at one side of the hook while the latter is maintained in a definite plane parallel to the garment form. The cooperating hanger for a second garment, such as skirt, trousers or the like is arranged to be loaded or emptied with a single motion without its removal from the combined device. In this way its use is simplified and rendered possible without disarranging the garment suspended from the garment form.

By way of example I have shown the preferred form of my device in the accompanying drawings in which,

Fig. 1 is a side elevation of a carrier,

Fig. 2 is an enlarged side elevation of the garment form and suspended hanger and

Fig. 3 is a perspective view of the supporting hook.

The frame of the carrier is formed essentially from the side members 5—5 which are made of wood or analogous material of appropriate length and sufficient width equal to that of the folded garments, thus serving

to confine them and enclose them from other articles which may be packed in the same luggage container.

The top member 6 of the frame of the carrier is formed from a round bar or rod of wood or like material and has a central portion 7 of enlarged diameter. Side portions 8—8 extend outwardly toward the side members 5—5 and are joined to them by the enlarged ends 9—9.

The bottom member of the carrier is shown at 10 to include a central portion 11 substantially larger than the enlarged portion 7 of the top member 6. Reduced portions 12—12 extend outwardly from the central portion 11 and terminate in enlarged ends 13—13 by which the bottom member 10 is attached rigidly to the side members 5—5.

A screw hook 14 is attached to the center of the top member 6 as shown in Fig. 1 and serves to hold the hangers for the garments. In order to economize space and also to adjust the space arrangement between the garment and the members 6 and 12 around which the garment is rolled or folded, particular use is made of a hook 15 of special shape. This hook has a shank 16 and the free end 17 is bent back parallel with the shank 16. A series of notches 18 is provided in the free end 17 for locking purposes. The free end 17 normally springs outward a slight distance due to the resilience of the material of which it is made.

The shoulder form 19 is shown to be flat and of conventional shape. At the center of one side it has attached a staple 20 extending transversely as shown in Fig. 2. Immediately beneath the staple 20 and on the same side of the form with it there is provided an eyelet or hook 21. As is evident from Figs. 2 and 3 this eyelet or hook 21 serves as a keeper to prevent the hook 15 from tilting sidewise with respect to the staple 20.

The eyelet 21 serves the additional purpose of a support for a yoke 22 made of spring wire or the like. One end 23 of the yoke is formed with an eye while the opposite end is bent back to form an open loop 24.

A cross bar 25 is pivoted to the eye 23 by means of a screw 26 mounted on one end of

the cross bar 25. The opposite end of the cross bar is adapted to be received in the open loop 24 and held there frictionally.

From the above description it will be evident that the hanger cross bar 25 and the shoulder form 19 are both suspended from the hook 14 on the carrier. Assuming that a suit of men's clothing is to be packed for transportation, the coat is slipped over the shoulder form in the usual way. By having the hook 15 on one side of the form 19, additional space is given the collar of the garment. The sleeves are folded back of the shoulders of the coat and fall naturally at the sides opposite the reduced portions 12-12 of the bottom member 10, when the garment holders are hooked into position.

The yoke 22 can be lifted out in front of the lapels of the coat and a folded pair of trousers slipped over the cross-bar 25 which is then engaged in loop 24. This is done without disturbing the hang of the coat and the trousers may then be slipped back of the open lapels of the coat. In order to adjust the device to suit garments of varying lengths, the shoulder form 19 with the garments hanging from it may be lifted along the shank of the hook 15 until the staple 20 is locked into position by the upper notch 18 of the free end of the hook. The device is then given a half turn to bring the bottom member 10 uppermost. The larger reduced portions 8-8 of the member 6 accommodate the change in position of the lower portion of the sleeves and the thick folds of the trousers. The carrier may be given one or more partial turns until the garments are completely wound around it.

The carrier and its load can now be laid flat in a drawer, compartment or luggage container without danger of creasing the garments. If packed in a vertical position the same advantages exist as the garments are practically hung or stretched between the top and bottom members. It is understood that the bulk of the garments is confined within the greater dimensions of the carrier so as to protect the garments from being too closely packed by other articles. In unpacking, the coat or shoulder form is unhooked from the frame and the garments hung in the closet in the usual way.

Other uses and changes in the details of the device will readily suggest themselves to those skilled in the art as being within the scope of the appended claims.

What I claim is:

1. A carrier for garments comprising a stretcher frame having sides, top and bottom members, a hook attached to the top member, a shoulder form adjustable lengthwise of the hook and means preventing the tilting of the form around the hook.

2. A carrier for garments comprising a stretcher frame having sides, top and bottom members, a hook having a looped shank and

being attached to the top member, a shoulder form slidably mounted along the side of the hook and means preventing the tilting of the form around the hook.

3. A shoulder form, a looped hook, a staple on one side of the form for adjustably holding the hook and a keeper on the form within the loop of the hook.

4. A shoulder form, a hook having a shank, a resilient member bent back parallel to the shank, a staple on the side of the form for holding both the shank and resilient member and a keeper on the form between the shank and the resilient member.

5. A shoulder form, a looped hook, a staple on the side of the form for holding the looped hook, an eyelet on the side of the form between the parts of the looped hook, and a garment hanger on the eyelet.

6. A carrier for garments comprising a frame having sides, a top member having a central portion of enlarged diameter, a bottom member having a central portion of enlarged diameter, a hook attached to the central portion of the top member, a shoulder form adjustably held by the hook, a yoke suspended from the shoulder form and a cross bar connecting the ends of the yoke.

In testimony whereof, I affix my signature.

ELDRIDGE R. BOYLE.
